WINDOW SASH

Leonard Christal, Lancaster, N. Y.

Application May 26, 1937, Serial No. 144,960

7 Claims. (Cl. 20—56.4)

This invention relates generally to window sashes, with more particular reference to non-vertically mounted panes, such as are essential to skylights and green-houses, where exposure to all manner of climatic and weather conditions is practically continuous, to say nothing of exposure to panel-breaking due to missiles or projectiles intentionally or unintentionally projected.

Therefore, one of the principle objects of my invention is the provision of a sash providing for the ready replacement of broken panes, also providing, as a correlative feature, for ready removal of broken-pane fragments. Incidentally, I also have in view means associated with sash-bars to insure snug-fitting and yet resilient relationship with the panes to minimize the effect of abnormal vibrations.

A preferred embodiment of my invention is disclosed in the accompanying drawing in which Fig. 1 is a front elevation of a window frame comprising sash and sash-bars embodying my invention;

Fig. 2 is an enlarged section taken substantially on the line 2—2 of Fig. 1;

Fig. 3 is an enlarged section taken substantially on the line 3—3 of Fig. 1;

Fig. 4 is an enlarged partly sectional detail view of a portion of Fig. 2; and

Fig. 5 is a detail perspective view of the cooperating pane-clamping members of the sash-bars.

I am aware that the provision of a soft-rubber or other pliable and elastic strip or rod mounted in the sash or sash-bars of a window frame is not new per se. Such members, generally speaking, are shown and described in patent to Tanner (December 26, 1882, No. 269,740), in patent to Umegaki (August 1, 1933, No. 1,920,722), in patent to Zand (February 19, 1935, No. 1,991,832), in patent to Stuart (September 29, 1936, No. 2,056,024), and possibly others. One of the prime objects of the present invention is to improve upon these structures with the purpose of practical differentiation primarily in view, and to incorporate in a new and useful improvement properties of cheapness of manufacture and assembly, together with efficiency, dependability and longevity in use.

Furthermore, I am aware that the stepped configuration of the pane-receiving and retaining members is not new per se. It is disclosed, for instance, in patent to Petri (April 10, 1877, No. 189,384), but it will be noted that Petri's stepped retaining rods or bars are of metal; that construction is through the medium of hinged

frames, with a screw-clamp to lock them together, whereby even slightly excess pressure is more than likely to result in fracturing the glass; and that his stepped retaining rods or strips are not adapted to engage the edges of medial panes but operate on panes extending throughout the width of the frame.

A preferred embodiment of my invention comprises a window frame of common and well-known configuration having top and bottom sash-rails 11 and 12 and side rails 13 and 14. I use the terms "top" and "bottom" for purposes of description, as it will be apparent that with the sash mounted in a substantially horizontal position there will be no longitudinal "top" or "bottom".

This frame includes the sash-bars 15 and 16. While I have shown but two of these bars, it will be apparent that any number thereof may be employed in meeting varying conditions. The configuration of these bars is best illustrated in Fig. 3, wherein I have shown each thereof provided with oppositely-disposed longitudinally-extending grooves or sockets 17 and 18 for the reception and retention of gaskets or strips of soft rubber, or other plastic and elastic material.

Each of these strips preferably comprises two sections, an upper section 19, initially of substantially rectangular cross-sectional configuration, and a lower section 20 having a rectangular groove at its outer and upper corner, whereby, when said sections are assembled and mounted, a slot 21 is provided for the reception and retention of the side or end edge portions of rectangular glass panes 22. It will be noted that the upper faces of the grooves 17 and 18 are outwardly inclined to provide for and enhance frictional engagement with the combined strip-sections 19 and 20. Further resilient pressure may be exerted through the rubber strips against the plane edges through the provision of nubs or bosses 23 on the metallic sash rail or bar at suitable intervals.

As clearly shown in Fig. 5, the cooperating sections of the rubber strips or gaskets are stepped at intervals, corresponding to the dimensions of the panes to be secured. Furthermore, the inner faces of the strip-sections between the steps are correlative inclined, whereby, as shown in Fig. 2, contiguous pane edges may be made to slightly overlap, in definitely determined although slightly yielding relationship.

Obviously, the sash-bars 15 and 16 are of duplex construction because a pane must be supported on

each side thereof, whereas the retaining means of the upper, lower and side rails 11, 12, 13, 14 need provide for the reception and retention of one pane-edge only. The top and bottom rails, as shown in Fig. 2, may be grooved for the insertion of the two-section rubber strips 19' and 20', while the side rails may be equipped or provided with one bifurcated section of the bar 15 (or 16), as shown by the dotted lines x—x 10 in Fig. 3. Or the rail itself may be similarly grooved to insure the same result.

Notwithstanding the patents to which I have referred, and possibly others, the type of sash-bar now more generally in use is adapted for the 15 mounting of panes of glass set in putty and stabilized by glazing nails or brads driven into the wood of the frame. It has been found that under continuous exposure to weather and climatic conditions the nails rust and are easily 20 dislodged, and sooner or later the putty hardens and becomes brittle and cracks and crumbles, with result that the panes slip or blow out when the wind gets above a normal velocity. This 25 means the dripping of water into the interior of the windowed structure and the escape of a great quantity of heat in cool weather—matters of much importance in greenhouse construction.

I claim as my invention—

1. A multiple-pane window-sash comprising 30 the usual sash-rails and transversely-disposed sash-bars, all provided with means for receiving and resiliently retaining under compressive forces individual glass panes arranged in vertical rows, the panes in each row having restricted 35 relative movement with reference to each other and with contiguous edges overlapping and in direct contact with each other, said means including supplemental means for augmenting the compressive forces acting upon the overlapping edges.

2. In a multiple-pane window-sash comprising the usual sash-rails and transversely disposed sash-bars, self-retained strips of pliant and resilient material peripherally arranged in said rails and bars, said strips comprising at least two layers of material which combine to provide a stepped groove to yieldingly receive and retain the glass panes individually.

3. In a multiple-pane window-sash comprising the usual sash-rails and transversely disposed sash-bars, self-retained strips of pliant and resilient material peripherally arranged in said rails and bars, said strips comprising at least two layers of material which combine to provide a stepped groove to yieldingly receive and retain

the glass panes individually in resiliently separated rows.

4. In a multiple-pane window-sash comprising the usual sash-rails and transversely disposed sash-bars, self-retained strips of pliant and resilient material peripherally arranged in said rails and bars, said strips comprising at least two layers of material which combine to provide a stepped groove to yieldingly receive and retain the glass panes individually in resiliently separated rows, contiguous end edges of the panes of each row being in directly contacting and overlapping relationship.

5. In a multiple-pane window-sash comprising the usual sash-rails and transversely disposed sash-bars, strips of pliant and resilient material peripherally arranged in said rails and bars, said strips comprising at least two layers of material which combine to provide a stepped groove to yieldingly receive and retain the glass panes individually in resiliently separated rows, contiguous end edges of the panes of each row being in directly contacting and overlapping relationship, and means supplemental to said pliant and resilient strips for augmenting the 25 normal compressive seating forces thereof.

6. In a multiple-pane window-sash comprising the usual sash-rails and transversely disposed sash-bars, strips of pliant and resilient material peripherally arranged in said rails and bars, said 30 strips comprising at least two layers of material which combine to provide a stepped groove to yieldingly receive and retain the glass panes individually in resiliently separated rows, contiguous end edges of the panes of each row being in 35 directly contacting and overlapping relationship and abutting suitable shoulders provided and suitably spaced in said sash rails to augment the normal compressive seating forces of said strips.

7. In a multiple-pane window sash comprising 40 the usual sash-rails and transversely disposed sash-bars, strips of plant and resilient material peripherally arranged and self-retained in said rails and bars, said strips comprising at least 45 two layers of material which combine to provide a stepped groove to yieldingly receive and retain the glass panes individually in resiliently separated rows, contiguous end edges of the panes of each row being in directly contacting and overlapping relationship, abutting suitable shoulders 50 provided and suitably spaced in said pliant and resilient strips, at least one of said sash-bars being provided with nubs to supplement the normal compressive seating forces of said strips.
